Primary Examiner — Daniel J Domino(74) *Attorney, Agent, or Firm* — FisherBroyles, LLP(57) **CLAIM**

The ornamental design for a display device or portion thereof with graphical user interface, as shown and described.

DESCRIPTION

This application claims the benefit of U.S. application Ser. No. 16/398,145, filed Apr. 29, 2019, U.S. application Ser. No. 16/398,148, filed Apr. 29, 2019, U.S. Provisional application Ser. No. 62/665,478, filed May 1, 2018, U.S. Provisional application Ser. No. 62/720,493, filed Aug. 21, 2018, and U.S. Provisional application Ser. No. 62/757,128, filed Nov. 7, 2018, the disclosure of each of which is incorporated, in its entirety, by this reference.

A drawing accompanies this disclosure. The drawing is a view of a display device or portion thereof with a graphical user interface.

The broken lines shown in the drawing illustrate portions of the display device or graphical user interface that form no part of the claimed design.
